UNITED STATES PATENT OFFICE.

FREDERICK E. HORNE, JR., OF PITTSFIELD, MASSACHUSETTS.

INTERNAL-COMBUSTION ENGINE.

1,219,639.

Specification of Letters Patent. Patented Mar. 20, 1917.

Application filed October 10, 1916. Serial No. 124,884.

To all whom it may concern:

Be it known that I, FREDERICK E. HORNE, Jr., a citizen of the United States, and a resident of Pittsfield, in the county of Berkshire and State of Massachusetts, have invented an Improvement in Internal-Combustion Engines, of which the following description, in connection with the accompanying drawings, is a specification, like characters on the drawings representing like parts.

This invention relates to an internal combustion engine or motor of that type in which a valve in the form of a sleeve is employed. The present invention has for its object to provide a sleeve valve of novel construction as will be described, which is capable of fitting tight in the cylinder under all conditions of temperature so as to obtain the desired compression of the gases, which automatically takes care of expansion and contraction without loss of compression and without sticking in the cylinder, which can be moved with a minimum of power and which is simple and inexpensive to construct.

To this end I employ a sleeve of any desired or suitable metal, which is provided with a split extended the full length of the sleeve at an angle to the axis thereof, and preferably at an angle of about 45°, and is provided with a suitable port opening or openings for the passage of the motive fluid and gases into and out of said sleeve and into and out of the cylinder in which the split sleeve is located. The split sleeve is arranged in the cylinder of the engine or motor, so as to leave one and preferably both of its ends free to move, whereby expansion and contraction of the metal sleeve is taken care of by axial movement of the split portions of the sleeve without changing the diameter of the sleeve to any material extent, if any.

The sleeve valve referred to, may be given any suitable motion, and in the present instance I have illustrated, one arrangement for rotating the sleeve valve, which I may prefer.

The particular features of the invention will be pointed out in the claim at the end of this specification.

Figure 1 is a vertical section of one form of single cylinder engine or motor embodying this invention.

Fig. 2, a cross section on the line 2—2, 55
Fig. 1.

Fig. 3, a cross section on the line 3—3, 60
Fig. 1.

Figs. 4, 5, 6 and 7, details of the sleeve valve, and 65

Fig. 8, a horizontal section of a four cylinder engine or motor to illustrate the manner of rotating the sleeve valves.

In Fig. 1 I have represented the invention as embodied in a single cylinder engine or motor, which may be of any suitable or usual construction and comprises the cylinder *a*, crank case *b*, crank shaft *c* and piston *d*.

The cylinder *a* contains within it a sleeve valve *e*, which in accordance with this invention is spirally divided longitudinally for its entire length, and said sleeve may be made of cast or drawn metal and cut or split spirally as indicated by the line *f* to form co-operating inclined edges 10, 12, or said spirally arranged sleeve may be rolled up or otherwise made. The sleeve valve *e* is normally of larger diameter than the internal diameter of the cylinder, as shown in Fig. 4, and is capable of being contracted and slipped into the cylinder to make a substantially tight fit therein and have the edges 10, 12 in contact (see Fig. 5).

The sleeve valve *e* is further arranged so that it is free at one end and preferably at both ends to move longitudinally or axially when expanded and contracted, and in the present instance, the upper end of the sleeve valve *e* is separated from the head 13 of the cylinder by a space 14, which in practice will be of sufficient size to permit of axial movement of one edge—10 of the sleeve *e* (see Fig. 6), and said sleeve at its lower end extends into the crank case *b* and its other edge 12 is free to expand therein.

The sleeve *e* is designed to fit the cylinder tightly when cold and to have the edges 10, 12, in contact, and when the sleeve is expanded under the influence of heat, the edges 10, 12, are caused to move axially in opposite directions when both ends of the sleeve are free, owing to the bevel or inclination of the cut or split, for, as the beveled or inclined contacting edges 10, 12, are forced against each other by the expansion of the metal in the sleeve, the opposing inclined surfaces or edges 10, 12, will be moved in opposite directions and axially or lengthwise with relation to each other.

tion to the sleeve as they are free to be so moved, and when the metal contracts the edges 10, 12, will be moved in the reverse direction. In this manner, the sleeve *e* remains of the same or substantially the same diameter under all conditions of heat and cold, and as a result a tight fit is obtained between the cylinder and the sleeve valve, whereby the desired compression of the gases within the cylinder is obtained to insure proper operation of the engine.

This relation between the sleeve valve and cylinder is maintained irrespective of the condition of the cylinder itself, for when the cylinder is cold and the sleeve valve *e* hot, the axial movement of the sleeve valve is such as to maintain the tight or substantially tight fit without sticking of the sleeve valve, and when the cylinder is warm or hot, the axial movement of the sleeve maintains the same tight or substantially tight fit with relation to the cylinder.

The sleeve valve *e* is provided with one or more ports according to the type of engine or motor with which it is used.

In the present instance I have illustrated the sleeve valve *e* as used in what is known as an L head motor, in which the inlet port 20 and the exhaust port 21 in the cylinder *a* are located on the same side and in proximity to one another.

In this case, the sleeve valve *e* is provided with a single port 22, which coöperates with both ports 20, 21, in the cylinder, but it is not desired to limit the invention in this respect, as the sleeve valve *e* may be provided with any desired number of ports to coöperate with the ports in the cylinder.

The port or ports 22 in the sleeve valve may be made on opposite sides of the split or as shown in the present instance, the port 22 may be formed with one half in each edge 10, 12, and arranged to form a full port as clearly shown in Figs. 4, 5 and 6.

In Fig. 5, the edges 10, 12, are shown in what may be considered their normal position within the cylinder, and in Fig. 6, the edges 10, 12, are represented as having been moved axially in opposite directions under the influence of heat.

By reference to Figs. 5 and 6, it will be observed that the diameter of the sleeve valve in its heated condition represented in Fig. 6 is the same as that of the sleeve valve in its normal condition represented in Fig. 5.

In the present instance, the sleeve valve is shown as having a rotary motion, which may be imparted to it from the crank shaft *c*.

To this end, the rotary sleeve valve *e* has fastened to it externally near its lower end a ring 24, which rests on and is adjustably fastened to a gear 25, supported on housings or segments of sleeves 26, which are stationary and are represented as fastened to brackets 27 attached to the crank casing *b*. The gear

25 is driven by a gear 30 on a shaft 31 having thereon a bevel gear 32, which is driven by a bevel gear 33 on a shaft 34 driven from the crank shaft *c* by gears 35, 36, or otherwise.

In Fig. 8, I have represented a four cylinder engine or motor in which the gears 25 on the sleeve valves of the cylinders are in mesh with one another, so that the sleeve valve of cylinder No. 1 drives the sleeve valve of cylinder No. 2, and the sleeve valve of No. 2 drives the sleeve valve of No. 3 and the sleeve valve of No. 3 drives the sleeve valve of No. 4.

While I have herein shown one method of rotating the sleeve valve, which I may prefer, it is not desired to limit the invention in this respect.

I have herein shown the invention as embodied in a sleeve valve, which is rotated, but it is not desired to limit the invention in this respect, as the sleeve valve may be given any other desired motion.

So also I have illustrated the joint in the split sleeve in Figs. 1 to 6, as a butt joint, but it is not desired to limit the invention in this respect, as the joint may be of any desired kind, and in Fig. 7, I have represented a locked joint.

The driving mechanism for the sleeve valve *e* is properly timed so as to close the exhaust port 21 when the inlet port 20 is open, and as shown in Fig. 2, the sleeve valve *e* is revolving in the direction of arrow 40 and is about to open the inlet port 20, which takes place on the suction stroke of a four cycle engine or motor. When the piston moves upward to compress the charge, the sleeve closes both ports 20, 21, which remain closed when the charge is ignited by the spark from the spark plug 41, and on the exhaust stroke of the piston, the exhaust port 21 is opened. When the piston is at the end of its compression stroke, the split portion of the sleeve is removed from the ports 20, 21, and a solid portion of the sleeve covers the same.

The sleeve valve *e* may be provided on its exterior surface with oil grooves 42 if desired or required.

From the above description, it will be seen that by providing the sleeve valve with a split, which extends for the length of the sleeve at an angle to the axis of said sleeve, so as to form coöperating inclined contacting edges, and arranging said sleeve valve within the cylinder so as to leave one end free to move, provision is made for taking care of the expansion and contraction of the sleeve of valve by axial movement of said sleeve, and as a result, the sleeve valve and the cylinder may be made of the same or different kinds of metal, as the coefficient of expansion of the metal or metals may be disregarded.

It will also be observed, that the sleeve valve fits the cylinder sufficiently tight under all conditions so as to obtain the desired compression of the gases.

5 So also sticking of the sleeve valve under excessive heat is also avoided.

It is preferred to leave the opposite ends of the sleeve valve free to move axially, but it is not desired to limit the invention in this 10 respect, as good results would be obtained so long as one end of the sleeve is free to move axially.

Claim:

15 In an internal combustion motor, in combination, a ported cylinder, a sleeve valve

having a port coöperating with the port in said cylinder and located in said cylinder to permit of axial movement of said sleeve valve, the latter being provided with a split which extends the length of the sleeve 20 at an angle to the axis thereof to form inclined edges which contact under conditions of use and coöperate to effect axial movement of said sleeve when the latter is expanded and contracted, means for moving said sleeve valve within said cylinder, and a piston movable in said sleeve valve.

In testimony whereof, I have signed my name to this specification.

FREDERICK E. HORNE, JR.
